JOSEPH H. ADAMS, OF BROOKLYN, NEW YORK.

OIL-CONVERTING PROCESS.

976,975.

Specification of Letters Patent. Patented Nov. 29, 1910.

Application filed February 25, 1908. Serial No. 417,713.

To all whom it may concern:

Be it known that I, JOSEPH H. ADAMS, a citizen of the United States, residing at Brooklyn, in the county of Kings and State of New York, have invented certain new and useful Improvements in Oil-Converting Processes, of which the following is a full, clear, and exact description, such as will enable others skilled in the art to which it appertains to make and use the same.

This invention, in contradistinction from fractional distillation processes, relates broadly to the art of essentially converting fluids, such as oils, into products of a dissimilar character; but, in its more intense aspect it consists in a thermal method of converting more or less refined mineral hydro-carbon oils, such as those of the kerosene series, into a more volatile product resembling the naphtha or gasoline series, which is characterized by a higher gravity with reference to the Baumé scale.

One object of this invention is to formulate a process of a commercially practical nature for carrying out the above stated conversion, (as essentially distinguished from a mere distillation), by means of an internal and properly applied source of heat, which is preferably derived from a submerged heater electrically maintained at an incandescent temperature.

As conducing to a better understanding of the ultimate basis of this invention, it may here be recalled that crude petroleum, by a process of fractional distillation, may be separated into a multitude of component oils differing from one another in insensible gradations. Commercially, the distillation is not carried to extreme limits of refinement, the aim being to produce the maximum yield of the three principal products for which there is the greatest demand, these being kerosene of 43° to 47° gravity constituting about 60° of the crude petroleum; naphtha of about 62° gravity constituting about 4% of the crude petroleum; and automobile naphtha, or, as it is more commonly called, gasoline, of about 68° gravity forming about 10% of the crude petroleum. Owing to the somewhat unsettled state of the nomenclature of mineral oils, these products sometimes go under modified names, particularly with respect to the "gasolines" which are today extensively sold under gravities considerably less than

has been customary some years past. The fact remains, however, that these products, however they be named, are not usually single distinctive oils, but as ordinarily found in commerce are in reality unseparated mixtures of higher and lower gravity oils having their components so proportioned that their average gravity conforms to the gravity, etc., of the kerosene, gasoline, or the like. Thus, an analysis by fractional distillation will show each of these commercial products to consist of a multitude of fractions ranging through a wide scale of gravities, although those which form the greater proportion of that product will possess gravities approximating the gravity of the product.

No commercially satisfactory method of converting oils such as those of the kerosene type into oils of higher gravity on the Baumé scale, such as those of the gasoline type, is at present known. It does not suffice to subject these commercial oils to the process of fractional distillation, for that merely serves to more or less perfectly separate the oils (which may be regarded as mixtures) into their component parts. However, by the herein disclosed process discovered by me it is now quite feasible to convert a low gravity oil as of the kerosene type into a higher gravity oil or mixture such as naphtha or so-called "gasoline." This I do by subjecting the oil or mixture of oils to the powerful influence of properly applied decomposing temperatures which will range from a visible or cherry red to a full white heat, according to character of the particular oil undergoing treatment.

The nature of the process is such that its full disclosure may be greatly facilitated by describing certain characteristic features of an apparatus adapted to carry out the same, in conjunction with statements detailing the manner in which the oil will course through and undergo essential change in quality in the various parts of the apparatus.

In the drawings like characters of reference denote corresponding parts through the several views of which:

Figure 1 is an assembly in elevation of the apparatus as organized for commercially carrying out my process. Fig. 2 is a sectional elevation showing one of the many possible forms of converter which may be employed for internally subjecting oil to an

incandescent temperature as contemplated by my process. Fig. 3 is a horizontal section taken through line 3—3 of Fig. 2.

Turning now to Fig. 1, A represents a suitable supply tank which serves as the source of the oil which is to be converted. As will be understood, this oil supply apparatus may assume diverse forms, but that shown in the drawings will be found to be quite suitable for ordinary usage. In this embodiment, the containing vessel 1 of the supply apparatus may be somewhat elevated with respect to the adjacent converter B so that the gravitating tendency of the oil may augment its flow into the converter under the influence of the more or less complete vacuum in such converter. A suitable frame 2 may be utilized as a support for the tank. The fluid oil may be admitted into the containing vessel or tank 1 by means of one or more suitable supply pipes indicated by 3, and this pipe may be connected by a tee with a vent pipe 5 rising from the top of the supply tank 1, and utilized for relieving such tank of any occasional undue pressure or partial vacuum, this being governed by the hand valve 6. Such tank 1 may also be provided with suitable gages 7 and 8, if desired. In like manner, gages 7' and 8' may be provided on the adjacent converter B. A pipe 9 connects the supply tank and converter in any desired manner, such as that shown.

The figures of the drawings show one of the many diverse forms which the converter may assume within the contemplation of this invention, and such converter here comprises a retort and heating section 12 surmounted by a cylindrical crown or dome 13. The supply pipe 9 in this form leads into the upper part of the retort section 12 which section forms the lower part of the converter. This section may be connected with the overlying dome by means of a gage 7', so that the condition and disposition of the contents of the converter may always be the more readily apparent and be susceptible of an intelligent variation by operating the hand valve 17 for regulating the flow of original oil through the supply pipe 9. The retort section 12 may also be provided in its lower end with a suitable drip or outlet pipe 18 which may be controlled by the hand-valve 19 shown in Fig. 1. By this means, the retort may be emptied of its contents and cleaned of any sediment which may have accumulated therein.

The dome or crown cylinder 13 is secured to the retort 12 by means of a suitably interposed flange member 20 which is suitably bolted to each of these respective sections. Inasmuch as the vapors rising into and filling the crown or dome 13 may at times be so rapidly evolved as to exert an undue pressure, I have arranged a cap 21 in close

fitting relation with the upper end of the cylindrical crown or dome, and have utilized, as a means for retaining the cap in position, a number of light cast iron clamps or springs 22 of such proportions and strength that they will break and release the cap at a pressure of from five to ten pounds to the inch. Of course, the retort and fittings are made as tight as possible, and therefore I have used between the several flanges and caps, gaskets of asbestos or other suitable material, so that the possibility of leakage may be obviated so far as may be necessary from a practical standpoint.

A feature of primary importance is the means for internally applying heat to the oil contained in the retort under a more or less complete vacuum for the purpose of bringing about a conversion of such oil. Preferably, this feature is electrically operated, and comprises one or more resistance rods or electrodes which are adapted to be maintained at a heat varying from a red to a white while submerged. In the shown form, this electric heater is made up in the form of a grid from a series of resistance rods arranged in pinion-like fashion, and so connected that the current may flow through the same to the best advantage. While the precise manner of connecting these resistance rods may be varied to conform to the different currents of electricity which may be commercially available, the form shown in Figs. 2 and 3 will be found very suitable for converting many forms of oil. This electric heater is especially adapted for working under an electric current having a relatively low voltage and a correspondingly high amperage. The current is brought in by means of a metallic conductor rod 23 which passes through the cap 21 at the summit of the dome, and, in order to prevent grounding of the current, an insulated bushing 24 of suitable material, such as soap stone, will be interposed in a tight fitting relation between such cap and the leading-in conductor 23. So also, a leading-out conductor 25 may similarly pass through the bottom of the retort section 12. The current will be taken from the mains 26 and 27 as will be obvious.

The conductors 23 and 25 terminate within the retort in electrical connection with the corresponding terminals of a suitably constructed electric heater H which comprises one or more electrodes 30. In my copending application 417,714, filed of even date herewith I have described and claimed an apparatus similar to that here mentioned, and as I have fully disclosed the structural character of such electric heater in said application, it will be unnecessary to elaborate thereon in this process disclosure. Suffice it to say, however, that this electric heater is of such character that certain of its parts

may be maintained at a high temperature ranging from a cherry red to a full white heat, even while submerged in the oil. This electric heater provides a means of internally heating the oil in such a manner as to very efficiently convert the same, and is thus adapted to assist in performing a step of primary importance to my process.

It may here be pointed out that, in operating upon certain classes of oils, that is, the more volatile oils, it is highly desirable to localize the application of the internal heat so as to prevent the spread, so to speak, of the heat in a lower degree of intensity than is necessary to efficiently "crack" the oil, but of a sufficient intensity to cause an evaporation of undue amounts of the oil at a distance from the electric heater without bringing about a conversion. To this end, in the embodiment of the apparatus shown by Fig. 2 I have provided a heat insulating shell 40 which provides a relatively restricted center channel for the upflow of the oil toward the electric heater. This heat insulating shell 40 rises above the level of the oil, and preferably has its upper end 41 in interfitting attachment with the overlying cylindrical crown or dome 13. Its lower end is, however, mounted upon a suitable perforate support 42 rising from the bottom of the retort. From this, it will be gathered that whenever the fluid to be converted is admitted into the retort and brought to the proper level indicated by the fluid gages, it will assume the same level on the outside of the insulating shell 40, as it will on the inside thereof. In this manner, the electric heater will be maintained in the predetermined submerged relation, and oil evolved as vapor will be constantly and uniformly replaced by fresh quantities of original untreated or non-converted oil. In other words, the oil within the center channel of the heat insulating shell 40 will be maintained at such a level as to cover the top of the incandescent electrodes of the electric heater, thus preventing explosion or other accident resulting from the ignition of oil vapors which might at times be mixed with air or other reactive agents. The insulating shell 40 being preferably constructed of a suitable heat insulating material, admirably serves to localize the heat just where it is most needed, *i. e.* in the immediate vicinity of the electric heater. On the other hand, the oil externally surrounding the heat insulating shell 40 within the retort 12 does not become heated to such a degree as to cause undue evaporation.

From the foregoing it will be seen that during the flow of the electric current, the electric heater will be maintained in a submerged relation at an incandescent temperature. The effect of this incandescent heat is to cause the oil which is in the immediate

vicinity of the incandescent electrode to be broken up or converted into oils having a higher gravity on the Baumé scale. The action is extremely violent, causing the cracked oil to become immediately vaporized and the uprise of this vapor brings about a furious local agitation in the oil. It may also be mentioned that owing to the excessive quantity of heat and owing to the fact that much of the heat will radiate at a diminished temperature into surrounding portions of the oil more distant from the incandescent electrode, considerable oil may be merely volatilized without undergoing conversion, just as burning oils and naphthas are boiled and vaporized without essential conversion in the ordinary processes of fractional distillation. By my apparatus, I am, however, able to reduce the undesirable volatilization without conversion to a minimum, and as a consequence the oils are in a large proportion cracked or converted in character. Oil will be constantly flowing toward and into contact with the incandescent electrode to take the place of that already vaporized. This newly admitted oil will in turn be cracked and changed in the apparatus into lighter or more volatile products. Thus, the complex mixture of the oils, known commercially as kerosene, may be changed by means of my process into a mixture of lighter oils which bears a general resemblance to and has the properties of what is commercially known as naphtha or gasoline. It may here be mentioned that during this operation, the raw or non-converted oils will be relieved of more or less of the carbon of which they are in part composed. This, of course, alters their chemical character and converts them from one or more of the products of the hydrocarbon series into others of an essentially different character. The carbon which is removed in this manner will be in part deposited upon the hot electrodes and in part precipitated in the adjacent oil, being to some extent held in suspension and to some extent gravitating through the oil toward the bottom of the retort.

Inasmuch as the precise degree of temperature at which the electric heater should be maintained in practice, will largely depend upon and vary with particular conditions, such as the composition of the raw oil to be converted, it will suffice to state that the temperature will generally vary from a cherry red to a white heat according to the fluid treated. When operating in this manner, it has been observed that apparently only a certain part of the fluid ultimately evaporated comes in direct contact with the incandescent electrodes for the reason that the conduction of the heat is sufficient to evaporate a certain somewhat remote portion of the oil at a lower temperature than

is requisite for the "cracking" of the oil. Accordingly, the vapors passing into the dome will be composed not only of the oil which has suffered a breaking up of its molecules by the high converting heat, but also will contain a certain proportion of the unchanged original oil in the form of vapor. These mixed vapors are evolved very rapidly owing to the incandescent temperature of the electrodes, and consequently care should be exercised to keep the oil line at the proper mark in the gage and not permit it to fall below or approach the danger line in which the incandescent electrodes would protrude above the level of the oil.

The mixed vapors pass from the dome or crown cylinder 13 into the discharge pipe 43, and thence through the pipe 44 into a suitable copper coil and water jacket condenser 45 mounted on a suitable support 46 and forming a part of the condensing apparatus C of Fig. 1. Since some of the vaporized original unconverted oil may tend to condense before reaching the condensing apparatus C, I prefer to connect the discharge pipe 43 with the bottom of the retort 12 by means of a drip pipe 47. This will enable the already-condensed unconverted oil to be readily passed into the retort again without first passing through the rest of the apparatus. I also prefer to provide the dome 13 with a safety or pop valve 48 mounted on the pipe 49 and may also add one or more pressure gages 49'.

After passing through the copper coil condenser and cooling tank apparatus C, the fluid oil passes into a reservoir or receiving tank D by means of pipe 50 shown in Fig. 1. The upper portion of this reservoir is connected with a suitable suction or vacuum apparatus F by means of pipe 51. Such vacuum apparatus may comprise a vacuum air pump 52 connected by a pipe 53 with a vacuum tank 54 provided with a gage 55 for the purpose of showing the degree of the vacuum. This vacuum pump may be conveniently operated in any desired manner, as by means of the electric motor 56 controlled by the rheostat 57 and switch 58 and geared to the vacuum air pump by means of the counter shaft and speed reducing apparatus 59. The utility of this vacuum apparatus in conjunction with the other features of my invention is very great, for thereby, I am enabled to reduce liability of explosion to a minimum, and, furthermore, materially promote uniformity and certainty in the operation of the entire apparatus. Thus, because of the low pressure (from five to ten pounds at the most) it is not necessary to depend upon gravity for the flow of oil from the main supply tank 1 to the converter, nor is it necessary to provide a force pump apparatus operating from the main supply tank. Because of the more or

less complete vacuum in the converter, the oil will flow from the supply tank, being sucked into the converter so to speak, and the rate of flow is under easy control by means of the hand valve 17. Moreover, since the vapors in the dome or crown cylinder 13 of the converter are maintained at a very low vapor pressure, there is very little chance of a serious explosion even though some air or other reacting substance should become mixed with the composite oily vapors. As the entire apparatus thus works under a more or less complete vacuum, it will be perceived that the condensed oil will not gravitate or flow out of the last reservoir or receiving tank 60 of the reservoir apparatus D. Accordingly, I have provided a means for withdrawing such oil by the apparatus E shown on Fig. 1; such apparatus comprising a suction pump 61 driven by a suitable motor 62 and gearing 63, and connected with the tank 60 by means of a suitable pipe 64.

The composite fluid oil withdrawn by apparatus F may either be directly returned to the converter in order to still further decompose the same into lighter products, or it may be subjected to fractional distillation or other operations to more or less completely segregate its components, and such components as may not be of the desired quality may then be returned to the converter for further treatment.

The above specifically described apparatus may of course be modified greatly and yet be well adapted to carry out one or more of the essential correlated steps of my process. It is apparent that I have succeeded in formulating a process well suited for achieving the several objects and ends in view, and that as a result I have made it possible to readily convert comparatively inexpensive commercially available oils into products of a greater value. Thus, kerosene of say 45° Baumé gravity may be readily changed into socalled gasolene of at least 67° Baumé gravity by successive treatments in accordance with my process.

In view of the foregoing disclosure, it will be obvious to those skilled in this art that my process may be carried out with different fluids from those specifically referred to, by varied steps, and with the assistance of different apparatus without however departing from the scope of my invention, and accordingly I intend that all matter contained in the above description shall be interpreted as illustrative and not in a limiting sense. I desire it also to be understood that the language adopted in the following claims is intended to cover all of the generic and specific features of the herein disclosed invention, and all statements of the scope thereof which, as a matter of language, might be said to fall therebetween.

Having described my invention what I claim as new and desire to secure by Letters Patent, is:

1. A process of the nature disclosed, consisting in internally applying to hydro-carbon oils an incandescent temperature of sufficient intensity to locally crack and convert the same into oils differing essentially in character from untreated oils.
- 10 2. A process for converting oils as contradistinguished from a process of fractional distillation, consisting in internally applying to an oil a decomposing incandescent heat, collecting and condensing the evolved vapors, and retreating the condensate as before.
- 20 3. A process of raising the gravity on the Baumé scale of oils as contradistinguished from the process of fractional distillation, consisting in maintaining a heat enduring body at an incandescent temperature while submerged in a mass of oil, and collecting and condensing the evolved vapors of converted oil.
- 25 4. A process of converting oils as contradistinguished from the process of fractional distillation, consisting in electrically maintaining an electrode at an incandescent temperature while submerged in a mass of oil whereby said incandescent temperature will produce a local decomposition or conversion of said oil.
- 35 5. A process of the nature disclosed consisting in maintaining a partial vacuum over a mass of oil within a suitable containing vessel, and locally applying to such oil an incandescent temperature adapted to precipitate carbon from said oil and convert the same into an oily product characterized by a higher gravity on the Baumé scale.
- 40 6. A process of converting oils as distinguished from fractional distillation processes which consists in maintaining a body of hydro-carbon oil of not less than thirty degrees Baumé gravity in a suitable containing vessel under a partial vacuum, and maintaining a heat enduring body at an incandescent temperature in submerged relation with respect to said oil.
- 45 7. The herein disclosed continuous method of raising the Baumé gravity of more or less refined mineral oils which consists in maintaining the original oil to be treated at an approximately average surface level within a closed containing-vessel, providing an electrode of heat-enduring material in submerged relation to said original oil near the surface thereof, causing a low-voltage, high-amperage electric current to flow through said electrode to maintain the same at an incandescent temperature while submerged in said oil, whereby said oil may be internally subjected to a local decomposing heat to decarbonize and rapidly convert the same, maintaining a partial vacuum over the

surface of said oil and withdrawing the vapors of the converted decarbonized oil, cooling and condensing such vapors, and admitting to said containing-vessel additional quantities of original oil to compensate for the withdrawals of converted oil.

8. The herein disclosed process of converting hydro-carbon oils of a less volatile nature into those of a more volatile nature, which consists in immersing in the oil an electric conductor adapted to withstand a protracted high temperature and providing a relatively large heating surface, said conductor being located in close proximity to the surface of said oil, causing a heavy current of low voltage to flow through said conductor while immersed, whereby it will be maintained at a temperature adapted to effect a rapid decomposition and vaporization of said oil, collecting the converted products and treating as before.

9. The herein disclosed process of effecting a decomposition of oils, which consists in completely submerging in oil near the surface thereof an electric high-resistance conductor having a large heat-enduring surface, causing a heavy electric current to flow through said conductor to maintain the same in a state of incandescence while submerged, maintaining a partial vacuum over said oil, supplying original oil as fast as evolved in converted form by said incandescent conductor, whereby the latter may be kept submerged, and finally rectifying the evolved converted vapors.

10. The herein disclosed continuous method of raising the Baumé gravity of more or less refined mineral oils which consists in maintaining the original oil to be treated at an approximately uniform average surface level within a closed containing-vessel, providing a high-resistance electrode of heat-enduring material in submerged relation to said original oil near the surface thereof, forcing through said electrode a current sufficiently heavy to maintain the same at an incandescent temperature while submerged in said oil, whereby said oil may be internally subjected to a local decomposing heat to decarbonize and rapidly convert the same, maintaining a partial vacuum over the surface of said oil and withdrawing the evolved vapors of the converted decarbonized oil from said vessel, cooling and condensing such vapors, and admitting to said containing-vessel additional quantities of original oil to compensate for the withdrawals of converted oil.

11. The herein disclosed process of effecting a decomposition of oils which consists in completely submerging in oil near the surface thereof an electric high-resistance conductor having a large heat-enduring surface, causing a sufficiently heavy electric current to flow through said conductor

to maintain the same in a state of incandescence while submerged, supplying additional oil to take the place of that evolved in converted form by said incandescent conductor, and condensing and retreating one or more of the converted products.

12. The herein disclosed process of decomposing mineral oils of the kerosene type into those having the characteristics of gasoline which consists in internally subjecting the kerosene to a localized incandescent temperature near its surface whereby it will be in part locally converted into gasoline vapor and will be in part vaporized without change, maintaining a partial vacuum over the oil, and withdrawing and rectifying the evolved gasoline-containing vapors.

13. The herein disclosed continuous method of raising the Baumé gravity of more or less refined mineral oils which consists in maintaining the original oil to be treated at an approximately uniform average surface level within a closed containing vessel, providing an electrode of heat-enduring material in submerged relation to said original oil near the surface thereof, causing a low-voltage, high-amperage electric current to flow through said electrode to

maintain the same at an incandescent temperature while submerged in said oil, whereby said oil may be internally subjected to a local decomposing heat to decarbonize and rapidly vaporize the same, withdrawing the evolved vapors of the converted decarbonized oil from said vessel, cooling and condensing such vapors, and admitting to said containing-vessel additional quantities of oil to compensate for the withdrawal of converted oil.

14. The herein disclosed mode of decomposing an oily mixture of the kerosene type into a product resembling gasoline which consists in locally and internally subjecting the same to an incandescent temperature, whereby it may be decomposed into a more volatile product with a concomitant precipitation of carbon, and repeating the process on such product until it closely resembles gasoline.

In testimony whereof I affix my signature, in the presence of two witnesses.

JOSEPH H. ADAMS.
